US00D849413S

(12) **United States Design Patent** (10) **Patent No.:** **US D849,413 S**
Lambertson, Jr. et al. (45) **Date of Patent:** **** May 28, 2019**

(54) **EXTENSION POLE MECHANISM FOR PAINT ROLLER**

(71) Applicant: **The Sherwin-Williams Company**,
Cleveland, OH (US)

(72) Inventors: **Michael C. Lambertson, Jr.**, Aurora,
OH (US); **Rita Forman-House**, Avon
Lake, OH (US); **Dennis P. De Renzo,
Jr.**, Concord Township, OH (US);
Michael O'Banion, West Minister, MD
(US)

(73) Assignee: **SWIMC LLC**, Cleveland, OH (US)

(**) Term: **14 Years**

(21) Appl. No.: **29/506,449**

(22) Filed: **Oct. 15, 2014**

Related U.S. Application Data

(63) Continuation of application No. 14/268,718, filed on
May 2, 2014, now Pat. No. 9,347,472, which is a
continuation-in-part of application No. 13/834,879,
filed on Mar. 15, 2013, now Pat. No. 9,328,755.

(57) **CLAIM**

The ornamental design for an extension pole mechanism for
paint roller, as shown and described.

DESCRIPTION

FIG. 1 is a side perspective view of an extension pole
mechanism for a paint roller;
FIG. 2 is a side view of a first housing of the extension pole
mechanism for paint roller shown in FIG. 1;
FIG. 3 is an interior view of the first housing of the extension
pole mechanism for paint roller shown in FIGS. 1 and 2;
FIG. 4 is a side view of a second housing of the extension
pole mechanism for Paint Roller shown in FIG. 1;
FIG. 5 is an interior view of the second housing of the
extension pole mechanism for paint roller shown in FIGS. 1
and 4; and,

(Continued)

FIG. 6 is an alternative side perspective view of the extension pole mechanism for paint roller shown in FIG. 1.
